UNITED STATES PATENT OFFICE

2,027,627

GRINDING MACHINE

Harold L. Blood and Alfred P. Burns, Worcester, Mass., assignors to The Heald Machine Company, Worcester, Mass., a corporation of Massachusetts

Application August 8, 1933, Serial No. 634,210

25 Claims. (Cl. 51—95)

The present invention relates to a grinding machine for the reduction of workpieces to a predetermined size, and it is particularly applicable to machines for grinding the internal surfaces of sleeves, bushings, or like articles.

In grinding machines of the type disclosed in United States Letters Patent No. 1,682,672, issued August 28, 1928 to Guild, and Patent No. 1,731,719 issued October 15, 1929 to Kempton and Gallimore, the crossfeed movement by which the grinding wheel is fed against the workpiece is procured in response to the longitudinal reciprocations of the table. This type of crossfeed movement results necessarily in a step-by-step crossfeed movement so that the pressure of the grinding wheel against the workpiece is not uniform. It is accordingly the principal object of the present invention to provide a mechanism by which the crossfeed movement may be uniform and may occur at a predetermined rate during the grinding operation. The invention also provides for varying the rate of crossfeed movement during the grinding operation.

In machines of the type disclosed in the above cited patents, the crossfeed movement is automatically discontinued during the runout of the table for a dressing operation which occurs during the grinding operation. In providing for a uniform crossfeed movement, instead of the step-by-step crossfeed movement of the prior constructions, use is made of fluid pressure actuated mechanisms which operate independently of the table movement, and accordingly the crossfeed movement is not discontinued when the table is given an extended movement for the dressing operation. It is accordingly a further object of the present invention in connection with a crossfeed movement actuated by fluid pressure responsive means to provide for a temporary cessation of the crossfeed movement while the dressing operation is taking place.

In the use of a centerless work-supporting structure of the type disclosed in the Einstein Patent No. 1,772,932, issued August 12, 1930, it is desirable to provide a structure for removing the finished workpiece from within the work-supporting structure and inserting an unground workpiece therein. The copending Highborg application Serial No. 266,287, filed March 31, 1928, now Patent No. 2,003,713, dated June 4, 1935, provides for the discharge of a finished workpiece and the positioning on an unground workpiece within the work-supporting and rotating structure and involves an extended movement of the pressure wheel forming a part of the work-sup-

porting structure which permits the finished workpiece to drop from within said work-supporting structure. No ejecting or discharge mechanism for positive removal of the workpiece is provided. The copending application of Einstein, Booth and Haas, Serial No. 374,556, filed October 25, 1932, discloses an ejector mechanism which is actuated by fluid under pressure and involves a downward movement of the ejector mechanism into engagement with the workpiece and subsequent upward swinging movement of the ejector for removal of the workpiece, an unground workpiece falling, by gravity, into grinding position.

The present invention is, in certain respects, an improvement on these patents and copending applications by the provision of an ejector which procures a positive ejection of the workpiece radially of the work-supporting structure and causes the unground workpiece to be properly positioned within the work-supporting structure. Other and further objects and advantages of the invention will appear from the following detailed description taken in connection with the accompanying drawings in which:

Fig. 1 is a front elevation of a machine embodying the invention.

Fig. 2 is a vertical sectional view substantially along the line 2—2 of Fig. 1 and showing the grinding wheel in operative position.

Fig. 3 is a fragmentary elevation showing the gage structure, parts being broken away to show more clearly the construction.

Fig. 4 is a vertical sectional view showing the driving means for the regulating wheel and the structure for actuating the ejector.

Fig. 5 is an end elevation of the structure of Fig. 4.

Fig. 6 is a vertical section along the line 6—6 of Fig. 1 showing the crossfeed mechanism.

Fig. 7 is a vertical section substantially along the line 7—7 of Fig. 6.

Fig. 8 is a sectional view substantially along the line 8—8 of Fig. 6 with parts broken away.

Fig. 9 is a vertical section substantially along the line 9—9 of Fig. 8.

Fig. 10 is an enlarged elevation of the control structure mounted on the front of the machine.

Fig. 11 is a fluid pressure diagram.

Like reference characters refer to like parts in the different figures.

Referring first to Fig. 1, the machine provides the usual reciprocating table 1 provided in an internal grinding machine; either the grinding wheel or the work to be ground is carried on said table, the reciprocations of the latter operating

in either case to produce a relative translatory movement between said grinding wheel and the workpiece. In the construction shown, the table supports and carries a workhead 2 and the wheelhead 3 is mounted on a bridge 4 which spans the guideways, not shown, provided by the base 5 of the machine for the movements of the table 1. The grinding wheel 6 is carried on a spindle 7 journaled in the wheelhead 3 and is suitably rotated at a high rate of speed by any well-known mechanism, not shown. The workpiece *a*, Fig. 2, is mounted in the work-supporting structure on the workhead and is also rotated at a slow rate of speed, as will hereinafter appear.

15 The reciprocations of the table 1 which cause the rotating grinding wheel to make the desired traverse over the surface of a workpiece in the work-supporting structure are imparted in any well-known manner as by the use of fluid pressure controlling and reversing mechanism, one type of which is described in Patent No. 1,582,468, issued to Heald and Guild April 27, 1926. It is sufficient to note for the purpose of the present application that reversal of the table is procured 20 at each end of the normal working stroke by spaced adjustable dogs 8 and 10 which are carried by blocks 11 and 12 adjustably mounted on the table 1 and which are adapted alternately to engage and move a reversing member 13. The 25 latter provides spaced upwardly projecting lugs 14 and 15 (see Fig. 10) which, during the grinding operation, when the workpiece is reciprocated back and forth over the grinding wheel, are situated in a position to be engaged by the dogs 8 and 30 10 respectively. The movements of the member 13 procure reversal of the movements of the table 1 through suitable mechanism to be described later.

Referring now to Fig. 11, fluid under pressure, 40 which is supplied by a pump 16, is directed through suitable valve mechanisms to the inlet port 17 of a casing 18 in which a reversing valve 20 is positioned. The valve casing has outlet ports 21 and 22 connected by pipes 23 and 24 to the right and left hand ends respectively of a cylinder 25 mounted within the base of the machine. A piston 26 is slidable within the cylinder and has a projecting piston rod 27 which is secured to a depending lug 28, Fig. 4, on the under side of the 45 table 1. The reversing valve 20 alternately directs fluid under pressure to opposite ends of the cylinder for urging the table 1 alternately to the right and to the left. At the same time, fluid exhausts from the opposite end of the cylinder 50 through an exhaust port 29 provided by the casing 18.

As shown in Fig. 11, the left hand end of the cylinder 25 is provided with spaced ports 30 and 31. The port 30 at the extreme end of the cylinder is connected by a channel 32 in which a ball check valve 33 is positioned to a channel 34 which connects the end of the pipe 24 to the port 31. The latter is spaced from the left hand end of the cylinder sufficiently to be covered and closed by 65 the piston 26 before said piston reaches the left hand end of the cylinder. Thus, as the piston moves into the position shown, and closes the port 31, further exhaust of fluid from the left hand end of the cylinder is cut off, as the ball check valve 70 33 prevents discharge of fluid through the port 30. The table is thus brought to rest under the cushioning action of the fluid locked in the end of said cylinder. When the reversing valve 20 is shifted for movement of the table to the right, fluid under 75 pressure enters the left hand end of the cylinder

past the check valve 33 for shifting the piston 26.

The reversing member 13 is connected to the reversing valve 20 for actuating said valve in response to the shifting movements of said member. As best shown in Fig. 10, the forward end 5 of the reversing valve 20 has secured thereto an arm 35 which supports a pin 36 in spaced relation to the center line of the valve. Said pin is positioned between spaced projecting lugs 37 and 38 on the end of an arm 40 secured to a shaft 41 journaled in the control box 42 on the front of the machine. The reversing member 13 is also secured against turning movement on the shaft 41 so that said member and the arm 40 move as a unit. The arm 40 has a V-shaped projecting portion 43 which engages with a corresponding V-shaped lug 44 on the end of an arm 45 pivotally mounted on a pin 46 carried by a bracket 47 secured within the control box. The arm 45 is urged upwardly into engagement with the V-shaped portion 43 by a spring 48.

As will be apparent from the drawings, the spacing between the lugs 37 and 38 is materially greater than the diameter of the pin 36 to provide a lost motion between the arm 40 and the reversing valve. As the arm 40 is rocked clockwise by the reversing dog 8, the V-shaped portion 43 slides along the side of the V-shaped lug 44 with which it is in engagement until the points of the V-shaped portion and lug pass each other. The arm 40 is then moved positively clockwise a further distance by the action of the spring 48 and procures a shifting movement of the valve 20. A positive reciprocation of the table is thus procured in response to oscillation of the reversing member 13 by the reversing dogs 8 and 10.

For shifting the reversing valve manually in setting up the machine, the arm 40 carries a pin 50 which is positioned between spaced arms 51 and 52 provided by a plate 53. The latter is secured to a shaft 54 journaled in the control box, and said shaft projects through the cover 55, Fig. 1, of the control box and carries on the forward end thereof a lever 56 which provides for manual turning movement of the shaft. Oscillation of the plate 53, as will be apparent, will shift the arm 40 and accordingly procure a turning movement of the reversing valve. The arms 51 and 52 are spaced apart a distance substantially greater than the diameter of the pin 50 to permit the arm 40 to rock without a corresponding movement of the lever 56.

The crossfeed movement between the workpiece and the grinding wheel is obtained by transverse movement of the wheelhead 3 on the bridge 4. The wheelhead is mounted on a cross-slide, not shown, and movement of said cross-slide is obtained by rotation of a crossfeed screw 57, Fig. 7, which engages an internally threaded portion, not shown, of the cross-slide. Said crossfeed screw carries a gear 58 on the forward end thereof, which meshes with a pinion 60 secured against turning movement on a shaft 61 journaled in a casing 62 in which the crossfeed mechanism is positioned. The casing 62, as best shown in Fig. 1, is secured to the forward end of the bridge. The pinion 60, during the crossfeed movement of the table, is rotated in unison with a ratchet wheel 63 which is positively actuated by fluid under pressure as hereinafter described. The rotation of the pinion 60 procures, through rotation of the screw 57, a movement of the grinding wheel transversely of the machine to cause the wheel to cut successively deeper and deeper into the workpiece.

The shaft 61 has journaled thereon an annular member or sleeve 64 having an integral pinion 65, and a vertically extending rod 66, Fig. 1, has rack teeth 67 thereon which are held in engagement with the teeth on the pinion 65 by a roller 68 journaled on a pin 70 secured to the casing 62. The rod 66 is positively reciprocated vertically for procuring a crossfeed movement during its upward movement and a subsequent retraction of the crossfeed movement when the rod moves downwardly.

The sleeve 64 has a flange 71 thereon with a tapered peripheral surface 72 which engages a correspondingly tapered internal surface 73 of an annular member 74 journaled on the member 64. A nut 75 which engages a threaded portion of the sleeve 64 procures a positive engagement between the surfaces 72 and 73 to prevent a relative turning movement between the sleeve 64 and the annular member 74.

The annular member 74 has spaced studs 76 and 77 secured by nuts 78 and 80 to said member, and said studs provide pivotal supports for pawls 81 and 82, Fig. 8, respectively. Said pawls are normally maintained resiliently in engagement with the ratchet wheel 63 by a spring 83. The pawl 82 procures clockwise turning movement of the ratchet wheel in response to a corresponding clockwise rotation of the gear 65 and the pawl 81 procures counterclockwise turning of the ratchet wheel when the gear 65 is turned counterclockwise. When both pawls are in engagement with the ratchet wheel, the latter rotates as a unit with the gear 65.

During the crossfeed movement of the grinding wheel, which involves a clockwise rotation of the sleeve 64, the member 74, and the pawls thereon, are advanced clockwise and, as the grinding operation continues, a pin 84 on the pawl 81 is brought into engagement with a shield 85 adjustably positioned in the casing 62. Said shield procures retraction of the pawl 81 out of engagement with the ratchet wheel 63. The crossfeed movement continues, however, under the action of pawl 82, and this movement carries the pin 84 onto the shield 85. During a subsequent retraction of the crossfeed movement by a counterclockwise turning movement of the sleeve 64, however, the annular member 74 turns counterclockwise relative to the ratchet wheel 63, since the pawl 81 is inoperative, until the pin 84 is carried counterclockwise out of engagement with the shield 85. Said pawl is then returned into engagement with the ratchet wheel 63 by the spring 83, and said wheel 63 then rotates as a unit with the annular member and the sleeve 64 during the remainder of the retracting movement. The relative turning movement between the annular member 74 and the ratchet wheel 63 during the retracting movement provides a compensation for the reduction in size of the grinding wheel, as will hereinafter appear.

Since the movement between the ratchet wheel 63 and the annular member 74, which provides the compensation for the reduction in size of the grinding wheel, is dependent upon the position of the shield 85 relative to the pin 84 at the end of each grinding operation, said shield is adjustable so that the extent of the compensatory movement may be varied in order to correspond approximately to the reduction in size of the grinding wheel. Referring now to Fig. 9, the shield 85 is carried by a plate 86 secured against rotation on a shaft 87, the latter having secured to its opposite end a knurled nut 88. The casing 62 is pro-

vided with an arcuate slot 90 concentric to the shaft 61, and this slot receives a sleeve 91 having a shoulder 92 which engages the inner surface of the casing. A nut 93 on a threaded portion of the sleeve engages the outer surface of the casing for clamping the sleeve in fixed position in the arcuate slot. The shaft 87 is slideable within the sleeve 91 and a spring 94 within the sleeve, and surrounding the shaft 87 urges the latter toward the left, Fig. 9, to urge the knurled nut 88 against the end of said sleeve, thereby maintaining the shield 85 in a position for engagement with the pin 84 on the pawl. The plate 86 has a projecting stud 95 which engages with one edge of the slot 90 to aid in maintaining the shield in proper position.

The knurled nut 88 which is positively secured to the shaft 87 has a projecting pin 96 engaging a recess in the sleeve 91. The shield 85 is withdrawn from operative position by movement of the nut 87 to the right, thereby drawing the shield to the right therewith, and subsequent turning of the nut to cause the pin 96 to engage the end of the sleeve 91 in a position spaced from the recess which normally receives said pin. The shield 85 is thus retained in inoperative position, when desired, to avoid any compensatory movement. The operative position of the shield 85 may be readily adjusted by loosening the clamping nut 93 and shifting the position of the sleeve 91 in the slot 90.

In setting up and adjusting the machine for the grinding of a predetermined size of workpiece, it is desirable to provide for rotation of the annular member 74 manually relative to the ratchet wheel 63. For this purpose, the annular member 74 has a shaft 97, Figs. 6 and 7, journaled therein to the inner end of which is secured an eccentric disc 98, in a position for engagement with projecting lugs 100 and 101, Fig. 8, on the pawls 81 and 82 respectively. The forward end of the shaft 97 is provided with a pinion 102 for engagement with a series of gear teeth 103 provided by a ring 104 which is rotatable on a shoulder 105 on the annular member 74 and is held against removal therefrom by washers 106 on screws 107 engaging the annular member. A manual turning movement of the ring 104 positions the eccentric disc in engagement with the lugs 100 and 101, thereby withdrawing both of the pawls 81 and 82 out of engagement with the ratchet wheel. The ratchet wheel 63 is then free to turn independently of the annular member 74.

The annular member 74 also carries a cam 108 which becomes operative during the grinding operation for reducing the rate of crossfeed movement, as will appear hereinafter, and this cam is properly positioned relative to the sleeve or actuating member 64 by loosening the clamping nut 75, thereby providing for a relative turning movement of the annular member 74 on said sleeve 64. The position of the cam 108 at the beginning of the grinding operation is thus easily adjusted and the rate of crossfeed movement is accordingly reduced at the desired point in the grinding operation. A crossfeed movement is manually procured by a hand wheel 110 having a hub which engages a portion 111 of the shaft 61 and which is clamped against a shoulder 112 on said shaft by a clamping nut 113 engaging the end of said shaft. Rotation of the hand wheel turns the pinion 60 and thus rotates the crossfeed shaft 57. During the manual crossfeed movement the pawls 80 and 81 are withdrawn from the ratchet wheel 63, as above pointed out.

The rod 66 by which the gear 65 is rotated, for procuring the crossfeed movement, is actuated by fluid under pressure. Referring to Fig. 11, the rod 66 is a continuation of a piston rod 114 secured to a piston 115 slideable in a cylinder 116 secured, as shown in Fig. 1, to the base of the machine. Fluid under pressure from the pump 16 passes through a pipe 117 to a channel 118 in a casing 120 having a longitudinal bore 121 in which a valve member 122 is slideable. The channel 118 intersects the bore 121 and a channel 123 in the casing 120 also intersects the bore at a point substantially opposite to the intersection of the channel 118. The channel 123 is connected by a pipe 124 to a channel 125 in a casing 126 having a longitudinal bore 127 in which a valve member 128 is slideable. The channel 125 intersects the bore 127 substantially opposite to the intersection of said bore with a channel 130 in which a manually controlled throttle valve 131 is positioned. The channel 130 intersects a channel 132 which opens into the bore 127 at a point spaced from the intersection of the channel 125 therewith. The casing 126 also has a channel 133 therein which intersects the bore 127 and is connected by a pipe 134 to a valve casing 135 in which a valve 136 is positioned. A channel 132' intersects the channel 130 and also intersects the bore 127 substantially midway between the openings from the channels 130 and 132 into said bore.

With the valve members 122 and 128 in the positions shown, these being the positions of said valves at the beginning of the grinding operation, fluid under pressure is admitted to the pipe 134 from the pump by passing around a reduced portion 137 of the valve member 122 which provides a fluid connection between the channel 118 and the channel 123 and around a reduced portion 138 of the valve member 128 which provides a fluid connection between the channel 125 and the channels 132 and 132'. A second reduced portion 140 on the valve 128 spaced from the reduced portion 138 by a full-size portion 141 provides for fluid connection between the channel 132 and the channel 133. Fluid under pressure thus enters the casing 135, but the flow of fluid through said casing to the cylinder 116, to which said casing is connected, is normally prevented by the valve 136.

The casing 135 has an outlet port 142 connected by a pipe 143 to a port in the lower end of the cylinder 116, said port being normally closed by the valve 136. The upper end of the cylinder is connected by a pipe 144, and a pipe 145 connecting therewith, to a channel 146 in the casing 120. A channel 147 which intersects the channel 146 also intersects the longitudinal bore 121 and fluid connection is normally provided from the channel 147 to an exhaust channel 148 in the casing 120 by a reduced portion 149 of the valve member 122 adjacent the right hand end thereof. The valve 136 is moved manually to the left, Fig. 11, against the tension of a spring 150 positioned within the casing 135, by pressure on a button 151 on the end of the valve stem 152 of the valve 136, said button being accessible from the front of the machine as shown in Fig. 1. When movement of the valve 136 to the left occurs, fluid under pressure from the pipe 134 passes around an annular groove 153 in said valve and into the pipe 143 to the lower end of the cylinder 116. This procures an upward movement of the piston 115 and a corresponding clockwise movement of the gear 65 for procuring a transverse or radial movement of the grinding wheel relative to the workpiece.

During upward movement of the piston 115, fluid above said piston exhausts through the pipe 145 to the exhaust channel.

The valve 136, which is manually controlled, as above stated, provides for a rapid transverse movement of the grinding wheel to bring the grinding wheel and workpiece into operative position. During the normal operation of the machine, while the workpiece and grinding wheel are in engagement, the crossfeed movement occurs at 10 a predetermined slow rate of speed by throttling the flow of fluid to the lower end of the cylinder 116. Referring again to Fig. 11, the pipe 134 is connected by a branch pipe 154 to a channel 155 in a casing 156. The channel 155 intersects a vertical channel 157 and the latter intersects at its upper end a bore 158 in which a throttle valve 160, for controlling the rate of crossfeed movement, is positioned. The bore 158 is connected by a short channel 161 to a vertical bore 162 in 20 the casing 156 in which a valve 163 is positioned, the latter being normally held in the position shown by a spring 164 positioned in the lower end of the bore 162. The valve 160 has a short longitudinal bore 165 in the end thereof and a 25 short lateral channel 166 intersects the bore 165 and provides fluid connection from the channel 157 into said bore. Turning movement of the valve 160 varies the size of the opening between the channel 157 and the channel 166 for controlling the amount of fluid passing therethrough.

The longitudinal bore 162 has an outlet port 167 connected by a pipe 168 to the pipe 143 which leads to the lower end of the cylinder 116. Fluid connection is normally provided between the channel 161 and the port 167 by a reduced portion 170 of the valve 163. As fluid under pressure is normally admitted to the pipe 134, as above pointed out, fluid under pressure also enters the channel 157 and the piston 115 moves upwardly 40 slowly at a rate determined by the setting of the throttle valve 160 which controls the size of the opening into the channel 166, thereby procuring a slow crossfeed movement of the grinding wheel.

The lower end of the channel 157 intersects a longitudinal bore 171 in which a throttle valve 172 is positioned. The bore 171 is connected by a channel 173 to the vertical bore 162. The vertical bore 162 also has an outlet port 174 connected by a short pipe 175 to the pipe 143. The valve 172 has a bore 176 longitudinally therein, and a short transverse channel 177 in said valve provides fluid connection from the channel 157 to the bore 176. Turning movement of the valve 172 varies the size of the opening into the channel 177, thereby determining the amount of fluid entering said bore. Fluid connection is normally provided between the channel 173 and the port 174 by a reduced portion 178 of the valve 163, said reduced portion being spaced from the reduced portion 170 by a full-size portion 180. The valves 160 and 172 have knurled knobs 181 and 182 respectively on the outer ends thereof to provide for manual adjustment of said valves, said knobs being accessible at the side of the machine, as shown in Fig. 1.

During the preliminary or rough grinding operation, fluid under pressure enters beneath the piston 115 through the valve 160 and also through the valve 172, the volume of fluid being adjusted by shifting the position of the valve 160. During the grinding operation, as the crossfeed movement continues, the cam 108, above referred to, is advanced clockwise into engagement with the upwardly projecting end 183 of the valve 163 and 75

procures a downward movement of said valve. By this downward movement, the opening from the channel 161 into the port 167 is closed by a full-size portion 184 of said valve above the reduced portion 170, thereby cutting off the flow of fluid through the valve 160. The crossfeed movement during the remainder of the grinding operation occurs at a materially slower rate of speed as determined by the setting of the valve 172, which constitutes a throttle valve for controlling the rate of crossfeed movement during the finish grinding operation. During the crossfeed movement, fluid from within the cylinder 116 above the piston 115 exhausts through the pipe 145 and the channels 146 and 147 to the exhaust channel 148.

The function and shifting movements of the valves 122 and 128, so far as they control the movements of the table, are fully described in the copending Blood and Burns application, Serial No. 681,334, filed July 20, 1933, now Patent No. 2,011,705, dated August 20, 1935. For the purposes of the present application it will be sufficient to note that the casing 120 (referring to Fig. 11) has a channel 185 spaced from the channel 118 and connected by a pipe 186 to a channel 187 in a casing 188 having a longitudinal bore 190 therein in which the main throttle valve 191 is positioned. The latter has a longitudinal recess 192 therein which is open to the inner end of the bore 190 and the end of said bore is connected by a pipe 193 to the inlet port 17 of the reversing valve casing 18. The throttle valve 191 has a rectangular notch 194 adjacent the intersection of the channel 187 with the bore 190 to provide fluid connection between the channel 187 and the recess in the valve. By the rectangular shape of the notch, the flow of fluid from the channel 187 is unthrottled regardless of the adjusted position of the throttle valve. With the valve 122 in the normal position shown, however, the flow of fluid from the channel 118 into the channel 185 is cut off by the full-size portion 195 of the valve 122 between the reduced portion 137 and the reduced portion 149.

The casing 126 has a channel 196 spaced from the channel 125 therein, and said channel 196 is connected by a pipe 197 to a channel 198 in the casing 188. The throttle valve 191 is provided with a V-shaped notch 200 adjacent the intersection of the channel 198 with the bore 190, thereby providing for adjustment of the flow of fluid from the channel 198 into the recess 192 in the valve by a turning movement of said valve. The latter has a forwardly projecting valve stem 201 which projects through the cover plate of the control box 42 on the front of the machine and has a lever 204 on the end thereof by which said valve may be manually positioned. Fluid connection is normally provided between the channel 125 and the channel 196 in the casing 126 by the reduced portion 138 of the valve 128 so that the normal movement of the table occurs at the speed determined by the setting of the throttle valve 191.

The workpiece *a* is supported in a centerless work-supporting structure mounted on the table 1. As shown in Figs. 2 and 4, the workhead 2 has a spindle 205 journaled therein and a regulating wheel 206 of large diameter is carried on the inner or right hand end thereof for engagement with the periphery of the workpiece *a*, as shown in Fig. 2. Forwardly of the regulating wheel 206 and in the same vertical plane is positioned a work-supporting wheel 207 mounted on a slide 208 adjustable on a bracket 210 secured to the

table. An adjusting screw 211 which is held against axial movement in a lug 212 on the bracket 210 engages the slide 208 to provide for adjustment of the position of the supporting wheel. The workpiece *a* is held in engagement with the regulating and supporting wheels by a pressure wheel 213 on a shaft 213' in the end of an arm 214 which is secured against rotation on a shaft 215 journaled in the workhead. The pressure wheel is resiliently held against the workpiece as will hereinafter appear. The spindle 205 is positively rotated by a worm gear 216 thereon engaging a worm 217 on a positively rotated shaft 218 which, in the construction shown, is a continuation of the shaft of the driving motor 219. Rotation of the wheel 206 procures a corresponding rotation of the workpiece *a* by engagement with the periphery thereof, this rotation of the workpiece being clockwise as seen in Fig. 2. The workpiece is thus supported and rotated on the cylindrical outer surface thereof during the grinding operation.

As shown in Fig. 3, the workpiece is held against axial movement by a rotating backing plate 220 which is rotatable about an axis coinciding substantially with the axis of the workpiece, and which is supported by antifriction bearings 221 in a part of the workhead. The backing plate has a cylindrical flange 222 which engages with the end surface of the workpiece, the latter being urged axially against said flange by the action of the roller 213, whose axis extends at a slight angle to the axis of the workpiece.

The grinding operation is under the control of gage members 223 and 224, Fig. 3, which are carried on the end of a gage rod 225 longitudinally slidably in the workhead. The gage rod extends through an opening 226 centrally of the backing plate 220 so that the gage members 223 and 224 are supported in alignment with the bore of the workpiece. The outer or left hand end of the gage rod 225 has an arm 227 journaled thereon and supported against axial movement thereon by bearing members 228. The lower end of said arm is secured against movement on the end of a rod 230 which is longitudinally slidable in a bore 231 in the workhead. The right hand end of the rod 230 projects to the right beyond the workhead as shown in Fig. 1 and is normally in alignment with the head of an adjustable screw 232 mounted in a bracket 233 on the bridge 4. A spring 234 in an opening 235 within the workhead surrounds the rod 230 and engages, at one end, a sleeve 236 on said rod, said sleeve being suitably held against movement on said rod. The other end of said spring engages a portion of the workhead for normally urging the rod 230, which is parallel to the gage rod 225, to the right, thereby urging the gages into contact with the end of the workpiece.

The rod 230 carries adjacent the arm 227 a forwardly projecting arm 237, in the outer end of which is positioned an adjustable screw 238 held in adjusted position by a locking nut 240, said screw, by its movement, controlling the progress of the grinding operation. At the beginning of the grinding operation, the bore of the workpiece is too small to permit entry of either of the gages therein, and the right hand movement of the screw 238 is limited by engagement of the smaller or roughing gage 223 with the end of the workpiece. As the grinding operation continues, the bore of the workpiece becomes large enough to permit entry of the roughing gage 223 therein, and the screw 238 accordingly moves to the right

beyond the normal right hand limit of its movement, a distance corresponding to the thickness of said roughing gage. This extended movement resulting from entry of the roughing gage within the workpiece procures a separation of the workpiece from the grinding wheel for a dressing operation on the wheel by a structure which will be disclosed hereinafter. After the dressing operation, grinding is continued until the bore of the workpiece reaches a size to permit the finish gage 224 to enter the bore thereof at which time a further extended movement of the screw 238 to the right takes place, thereby procuring cessation of the grinding operation and runout of the table to the rest position of Fig. 1.

The above described gage mechanism through the adjustable screw 238 actuates a control mechanism which is mounted on the front of the machine and which controls the grinding operation. The control mechanism is fully disclosed in the copending above cited application of Blood and Burns, Serial No. 681,334, filed July 20, 1933, now Patent No. 2,011,705, dated August 20, 1935. It is sufficient to note, for the present application, that, as best shown in Figs. 1 and 10, a lever 241, which is journaled on a shaft 242 positioned in the control box 42 has a depending arm or latch 243 which normally engages a notch 244 provided in a lug 245 on a depending arm 246 journaled on a shaft 247 in the control box. Said arm is urged counter-clockwise by a spring 248 which is positioned within a recess 250 in a bracket 251 mounted in the control box, one end of said spring engaging the inner end of the recess and the other end of said spring engaging said arm. A bell crank lever 252 which is journaled on the shaft 247 has a depending arm 253 which engages a pin 254 on the arm 246. The other arm 255 of the bell crank lever 252 projects upwardly between the lugs 14 and 15 on the reversing member 13 and is provided with a cam surface for engagement with the reversing dog 10 which is pivotally mounted on a pin 256 in the block 12.

The lever 241 has an upwardly extending arm 257 which projects through an opening 258 in the control box. The table 1 carries a block 260, Fig. 1, which supports a pin 261 on which a bell crank lever 262 is pivotally mounted. The latter is received within a slot in said block and is held frictionally against unintended movement therein. One end 263 extends substantially horizontally to the right and slightly above the upper end of the arm 257 and the opposite end 264 extends upwardly into horizontal alignment with the adjustable screw 238 connected to the gage mechanism. During the preliminary or rough grinding operation, the movement of the adjustable screw 238 to the right is limited by engagement of the roughing gage 223 with the end of the workpiece, as above stated, and the end of the adjustable screw approaches but does not rock the upwardly projecting arm of the bell crank lever 262. Upon entry of the roughing gage within the workpiece, however, the resultant extended movement of the gage members to the right shifts the end of the screw 238 into engagement with the lever 262 to procure a slight turning movement thereof, thereby moving the horizontal arm 263 downwardly into alignment with the end of the upwardly projecting arm 257 of the lever 241.

As the table 1 moves to the right, following the entry of the roughing gage within the bore of the workpiece, the end of the arm 263 engages and rocks the upwardly projecting arm 257 to procure

a clockwise turning movement of the lever 241, elevating the latch 243 of said lever out of engagement with the notch 244 provided on the arm 246. When the latch is disengaged from the notch, the depending arm 246 moves to the right under the action of the spring 248, thereby rocking the bell crank lever 252 to elevate the upwardly extending arm of said lever into alignment with the reversing dog 10. As the table moves to the left the reversing dog 10 is held out of engagement with the lug 15 by the arm 255, so that said table moves beyond its normal operative position to carry a dressing tool 265, Fig. 1, on the table, past the grinding wheel.

The dressing tool is moved by fluid under pressure from the inoperative position shown into operative position in alignment with the grinding wheel for engagement therewith during the extended movement. The fluid pressure mechanism for actuating the dressing tool, which is fully disclosed in the Heald and Guild Patent No. 1,779,094, issued October 21, 1930, will be described later in connection with the fluid pressure mechanism. On the return movement of the table to the right into operative position following the dressing operation, a roller 266, carried by the support for the dressing tool, engages a cam, not shown, on the back of the bridge 4 for returning the dressing tool to inoperative position.

After the dressing tool has passed the grinding wheel during the movement of the table to the left, a reversing dog 267 pivotally mounted on a pin 268 in a block 270 adjustably secured to the table engages a portion 271 of the lug 15. The portion 271 projects above and forwardly of the main portion of the lug engaged by the dog 10, and the upper end of the arm 255 in raised position, as a result of the swinging movement of the depending arm 246, does not elevate the dog 267 sufficiently to prevent engagement between said dog and the portion 271. Engagement of the dog 267 with the lug shifts the reversing valve, thereby reversing the direction of movement of the table to return the workpiece to operative position for the completion of the grinding operation.

During the return movement of the table to operative position, the upwardly projecting arm 255 is restored to the original position out of alignment with the reversing dogs 10 and 267 to prevent a repetition of the dressing operation. To this end, the block 270 carries a depending dog 272, Fig. 10, pivotally mounted on a pin 273 in said block. A portion of said dog engages a shoulder 274 on the block 270 to prevent clockwise movement of said dog from the position shown. During the extended movement of the table to the left, the depending dog 272 engages the upwardly extending end of the arm 255 and is swung counterclockwise on the pin 273 without affecting the position of said arm; on the return movement of the table to the right, however, said dog engages the upper end of the arm 255 and returns said arm to the position shown in Fig. 1 with the upper end of said arm out of alignment with the reversing dog 10. Downward movement of the arm 255 also returns the depending arm 246 to its original position where it is retained by a latch 275 pivotally mounted on a pin 276 on the depending arm.

Referring again to Fig. 10, a stud 277 mounted in the control box 203 provides a support for a lever 278 having a counterweight 280 at one end and a projecting lug 281 which engages with a bracket 251 for supporting said lever in the position shown. A pin 282 in a projecting lug 283 on

the lever provides a support for a member 284, a portion of which engages said lever to prevent clockwise turning movement of said member beyond the position shown. During the extended movement of the table to the left for the dressing operation, a projection 285, Fig. 1, on the end of a bar 286 carried by a block 287 on the table engages the upwardly extending end of the member 284, with which said projection is in alinement, and procures a counterclockwise turning movement of the lever 278. During the return movement of the table to the right, the projection 285 engages and rocks the member 284 without affecting the position of the lever 278.

15 The lever 278 has a pin 288 to which a rod 290 is connected and the lower end of said rod engages the end of a set screw 291 adjustably positioned in one arm of a lever 292. Said lever is pivotally mounted on a stud 293 in the control box and has a notch 294 in the upper surface thereof which provides a locking surface 295 for engagement with a projecting portion 296 on the latch 275. Said latch has a depending end portion 297 engaging with the lever 292 just above the stud 293. In addition to the notch 294, the lever 292 has a notch 298 on the under side thereof which engages with the left hand end of the valve member 122, Fig. 11, to prevent movement of said valve to the left. Upon counterclockwise turning movement of the lever 278, the right hand end of the lever 292 is elevated to raise said notch out of engagement with the end of said valve. The latter then moves to the left automatically, as will be pointed out hereinafter, to engage with a second and lower notch 299 in said lever. Said lever 292 is then supported by the end of the valve member 122 in the position shown in Fig. 10 and a return movement of the depending arm 246 to the original position of Fig. 1, in response to engagement between the dog 272 and the upper end of the arm 255, positions the projecting portion 296 of the latch in engagement with the surface 295 in the lever 292 so that the depending arm 246 is retained substantially in the position of Fig. 1 during the remainder of the grinding operation.

The swinging movement of the depending arm 246 to the right, above referred to, also procures a shifting movement of the valve member 128, Fig. 11, to the right for reducing the rate of movement of the table during the dressing operation, and for temporarily discontinuing the cross-feed movement. The arm 246 engages, at its lower end, in a notch 300 provided by said valve member. As shown in Fig. 11, fluid connection prior to the dressing operation has been provided directly between the channels 125 and 196 in the casing 126 by the reduced portion 138 of the valve 128, so that the rate of movement of the table is determined by the setting of the main throttle valve 191. Upon shifting movement of the valve 128 to the right by the arm 246, a full-size portion 301 of said valve cuts off the flow of fluid from the channel 125 directly to the channel 196 and directs the fluid through the channel 130 past the auxiliary throttle valve 131, and thence through the channel 132 to the channel 196, so that the amount of fluid entering the cylinder 25 is limited by the setting of said auxiliary throttle valve 131 which reduces the flow of fluid to an extent much greater than the reduction of flow by the main throttle valve 191.

During the same movement of the valve 128 to the right, the full-size portion 141 of said valve 75 cuts off the flow of fluid from the channel 132 into

the channel 133, thereby preventing any fluid from entering the cylinder 116 beneath the piston 115 which procures the crossfeed movement, and the crossfeed movement is accordingly discontinued during the dressing operation while the valve 128 is in its right hand position. The crossfeed movement is again started when the valve member 128 is returned to the position of Fig. 11 which occurs during the return movement of the table to operative position after the dressing operation. 5

As above stated, shifting movement of the valve 128 to the right also procures a movement of the dressing tool 265 into operative position. As shown in Fig. 11, the casing 126 has a channel 302 intersecting the longitudinal bore 127 at the left of the channel 125, and the channel 302 is connected by a pipe 303 to a channel 304 in the casing 126 for the valve 122. Said channel 304 intersects an annular groove 305 in the casing 126 surrounding the valve 122 to the left of the channel 118, and a channel 306 which intersects said annular groove is connected by a pipe 307 to a casing 308 in which a piston 309 is slideable. Fluid connection between the channel 125 and the channel 302 in the casing 126 is normally cut off by the full-size portion 310 of the valve 128, and fluid connection is provided between the channel 302 and an exhaust channel 311 in the casing 126 by a reduced portion 312 of the valve 128 at the left of the full-size portion 310. The valve 128 has a full-size portion 312' to the left of the reduced portion 312.

When the valve 128 is shifted to the right by the movement of the depending arm 246 to the right, fluid under pressure is admitted to the channel 302 directly from the channel 125 around the reduced portion 312 of said valve and passes from said channel 302 to the groove 305 and into the casing 308, the exhaust channel 311 being closed by the full-size portion 312' of the valve 128. The piston 310 is connected to the support in which the dressing tool is mounted by any suitable structure such as that disclosed in the above cited Heald and Guild Patent No. 1,779,094 so that, when fluid under pressure is admitted to the casing 308, the dressing tool is moved into operative position. On the return of the valve 128 to the position of Fig. 11, this movement occurring, as above stated, during the return of the table to operative position following the dressing operation, the full-size portion 301 again cuts off the flow of fluid under pressure into the channel 302 and the reduced portion 312 provides fluid connection between the channel 302 and the exhaust channel 311 to permit return of the dressing tool to inoperative position.

The valve member 122 has a full-sized portion 313 at the left of the reduced portion 137 and an enlarged portion 314 at the left of the portion 313, said enlarged portion providing a shoulder 315 which is normally positioned within the annular groove 305. When fluid under pressure passes from the channel 302 into the casing 308 by passing through the annular groove 305, fluid under pressure acting on the shoulder 315 urges the valve member 122 to the left. Movement of the valve, however, is normally limited by the notch 298 in the lever 292 above referred to. When the lever 292 is rocked, during the extended movement of the table to the left, this rocking movement occurring while fluid under pressure is directed into the annular groove 305 by the valve 128, the end of the valve is released 75

from the notch 298 and said valve is allowed to move to the left.

Movement of the valve 122 to the left procures a throttling action on the fluid passing from the channel 118 into the channel 123 so that the rate of travel of the table, during the remainder of the grinding operation, may be materially reduced. When the valve 122 reaches the left hand end of its movement, the right hand end of the reduced portion 137 of said valve partially closes the opening into the channel 123 from the bore 121 so that, following the dressing operation when the valve 128 has been returned to the position shown in Fig. 11 to permit direct fluid connection from the channel 125 to the channel 196, thereby eliminating the auxiliary throttle valve 131, the rate of movement of the table is controlled by the amount of fluid passing from the channel 118 into the channel 123, this amount of fluid being less than the throttled flow of fluid through the V-shaped notch 200 of the main throttle valve 191. When the depending arm 246 is returned to the position of Fig. 1 during the return movement of the table to operative position, the valve 128 is returned to the position of Fig. 11 to render inoperative the auxiliary throttle valve 131.

After grinding is resumed, following the dressing operation, the crossfeed movement continues and the grinding wheel enlarges the bore of the workpiece until the finish gage 224 is allowed to enter the bore of the workpiece. Entry of said gage provides an increased movement of the adjustable screw 238, secured to the gage structure, to the right to procure a further clockwise turning movement of the bell crank lever 262. This movement of the bell crank lever positions the horizontal arm 263 thereof in alinement with the upwardly extending end of an arm 316 of a lever 317, Fig. 10, journaled on the shaft 242 in back of the lever 241. Said lever 317 has a depending arm or latch 318 which engages a notch 320 in a lug 321 on a depending arm 322 journaled on the shaft 247 in back of the arm 246. Said arm 322 is urged to the right by a spring, not shown, directly in back of the spring 248 and engaging in a recess parallel to the recess 250 in the bracket 251. Clockwise turning movement of the lever 317, which occurs when the finish gage 224 enters the bore of the workpiece, elevates the arm 318 out of the notch 320 to permit the depending arm 322 to swing to the right. This movement of the arm 322 procures a runout of the table to the rest position of Fig. 1 and a retraction of the crossfeed movement.

Referring again to Fig. 10, the depending arm 322 has a pin, not shown, which engages a depending arm, also not shown, parallel to the arm 253 and integral with the bell crank lever 252, being connected thereto by a forwardly projecting connecting bar 323. Movement of the arm 322 to the left accordingly procures an elevation of the upwardly extending arm 255 of the bell crank lever 252 into alinement with the reversing dogs 10 and 267. At this time, the arm 255 is elevated sufficiently high to raise both of said dogs out of engagement with the lug 15 of the reversing member 13 so that the reversing valve is not shifted during movement of the table to the left, and the latter moves beyond its operative position into the rest position of Fig. 1 where it is brought to rest by the fluid pressure mechanism above described.

Movement of the arm 322 to the right also

procures a shifting movement of the valve 122 to the right for procuring retraction of the crossfeed movement and for procuring a rapid movement of the table to the left into the rest position. The depending arm 322 engages a groove 323' at the left hand end of the valve 122. When the valve 122 is shifted into the right hand position, fluid under pressure passes from the channel 118 around the reduced portion of said valve 137 into the channel 185 which, as above stated, is connected through the rectangular notch 194 of the throttle valve 191 to the reversing valve 18. Accordingly fluid under pressure free of any throttling action passes directly from the pump 16 to the reversing valve 18 and thence to the cylinder 25 so that the runout of the table to rest position occurs at the maximum rate of travel.

For retraction of the crossfeed movement, the valve 122 has a channel 324 therein which is open at one end to the reduced portion 137 of said valve 20 and at the other end enters into an annular groove 325 formed in the full-size portion 195 of said valve. When the valve 122 is shifted into the right hand position, at the end of the grinding operation, fluid under pressure from the channel 118 passes through the channel 324 into the groove 325 which is in alinement with the opening into the channel 147, thereby directing fluid under pressure through the pipe 145 and the connecting pipe 144 into the upper end of the cylinder 116 30 to procure a downward movement of the piston 115 and a corresponding retraction of the crossfeed movement.

The pipe 144 is connected by a branch pipe 326 to the upper end of a casing 327 in which a valve 328 is positioned. The casing 327 also has a port spaced from the pipe 326 and connected by a short pipe 330 to the pipe 168 from the casing 156 to the lower end of the cylinder 116. An exhaust port is also provided by the casing 327 and is spaced from the pipe connection 330, said exhaust port being provided with an exhaust pipe 331. The valve 328 which is normally maintained in the position shown by a coil spring 332 beneath said valve has an annular groove 333 substantially centrally thereof, and fluid connection from the pipe 330 to the exhaust pipe 331 is normally cut off by the full-size portion of the valve 328 below said annular groove 333. When fluid under pressure is admitted through the pipe 145 and a branch pipe 144 into the cylinder 116 fluid under pressure also passes through the pipe 326 into the casing 327 above the valve member 328 urging said valve member downwardly and providing a fluid connection between the pipe 330 and the exhaust pipe 331. When this occurs, fluid is allowed to exhaust from beneath the piston 115 through the pipes 143 and 168 and the branch pipe 330 into the exhaust pipe 331.

The shifting movement of the valve 122 also procures a retraction of the gage members from within the bore of the finished workpiece. As shown in Figs. 3 and 11, the workhead is provided with a longitudinal bore 334 in which a piston 335 is movable. A piston rod 336 projects to the left beyond the workhead and engages the head of an adjustable screw 337 in the arm 227 of the gage mechanism, said screw being locked in position by a nut 338. The piston 335 is normally urged to the right to withdraw the piston rod 336 from engagement with the screw 337 by a spring 340, one end of which engages the piston 335 and the other end of which engages a cap 341 positioned over the end of the bore 334. The right hand end of the bore 334 has a port 342 connected 75

5 by a pipe 343, Fig. 11, to the pipe 145. When fluid under pressure enters the pipe 145 for retracting the crossfeed movement, fluid is also directed into the bore 334 to the right of the piston 335 urging the latter to the left against the tension of the spring 340 and retracting the gages 223 and 224 from within the bore of the workpiece.

10 During the runout of the table to rest position 10 at the completion of the grinding operation, the finished workpiece or workpieces are removed from operative position and unground workpieces are positioned therein. As shown in Figs. 2 and 4, the spindle 205 which carries the supporting and rotating wheel 206 is hollow for the 15 reception of a shaft 344 journaled therein. The latter carries on the forward end thereof a plate 345 secured against movement thereon, and said plate has an ejector arm 346 which extends 20 transversely across the surface of the wheel 206 in spaced relation thereto, the arm being normally beneath the workpiece *a* as shown in Fig. 2. The plate 345, as shown in Fig. 2, has a slot 347 therein which receives the end of the 25 shaft 344 and a clamping nut 348 on the end of the shaft 344 supports the plate in adjusted position thereon. The left hand end of the shaft 344 has a bevel gear 350 secured against turning movement thereon, and said gear engages a bevel gear 351 secured against rotation 30 on the upper end of a shaft 352 journaled in a housing 353 secured to the table. An arm 354, Figs. 4 and 5, secured against rotation on the lower end of the shaft 352 has a roller 355 on the 35 end thereof which engages a cam 356 on a bracket 357 secured to the base of the machine. During the runout of the table to rest position, the cam 356 procures a turning movement of the shaft 352 and a corresponding clockwise rotation (Fig. 2) of the ejector arm 346 into the dot-dash line position of Fig. 2. During this movement, the upper surface of the arm 346 engages the workpiece in the work-supporting structure and carries it around the periphery of the supporting wheel 206 to the top thereof where it is 40 discharged toward the rear of the machine.

45 Referring again to Figs. 4 and 5, the shaft 344 carries a cam 358 adjacent the bevel gear 350, said cam engages a roller 360 on one end of a lever 361 journaled on a pin 362 secured to the housing 353. The opposite end of the lever has a flat surface 363 which engages with one end of a bell crank lever 364 journaled on the outer or left hand end of the shaft 215 to which the arm 214 carrying the pressure roller 213 is secured. The opposite arm 365 of the bell crank lever extends upwardly between the opposite legs 366 and 367 of a U-shaped member 368 secured against turning movement on the shaft 215. Set screws 50 370 and 371 are positioned in the legs 366 and 367 and engage opposite sides of the arm 365 to provide for adjustment of the bell crank lever 364 relative to the member 368. A rod 372, Figs. 1 and 5, extends upwardly from a lug 372' on the 55 workhead through a notch, not shown, in the end of the bell crank lever 364. A spring 373 surrounds the pin and engages the upper surface of the bell crank lever to maintain the latter in engagement with the surface 363. The upper end 60 of the spring 373 engages a threaded sleeve 374 which engages the upper threaded end of the rod 372. Turning movement of the sleeve 374 permits an adjustment of the tension of the spring 373, thereby varying the downward pressure on 65 the bell crank lever 364 and accordingly adjust-

ing the pressure exerted by the pressure wheel 213 against the workpiece. During turning movement of the shaft 344 for ejecting the workpiece, the cam 358 on said shaft rocks the lever 361 to procure a clockwise movement (Fig. 5) of the bell crank lever 364 and a corresponding retraction of the pressure wheel 213 (counterclockwise, Fig. 2) from engagement with the workpiece to permit the workpiece to be easily elevated by the ejector from within the work-supporting member. 10

15 As shown in Fig. 2, the table 1 has an upwardly extending portion 375 on which a bracket 376 is mounted, the latter having parallel slots 377 which are engaged by bolts 378 to permit adjustment of said bracket relative to the table. The 20 bracket 376 provides a U-shaped groove 380, Fig. 1, having a bottom surface 381 inclined downwardly toward the rear, and the rearward end of the surface 381 is in substantially vertical alignment with the forward surface of the rotating and supporting roll 206 to permit workpieces positioned in the U-shaped groove 380 to drop into the work-supporting member. The bracket 376 also provides an arcuate U-shaped groove 382 substantially parallel to the periphery of the roll 25 206 and in alignment with the workpiece *a* in the work-supporting member, said groove extending from a point slightly above the workpiece to a point directly above the upper position of the ejector arm and intersecting the groove 380. 30

25 The workpieces in the groove 380 are normally urged by gravity toward the rear into the position shown in Fig. 2 and are prevented from passing beyond the position shown by an arm 383 which engages the bracket 381 in alignment with the 35 workpieces in the groove 380. The arm 383 is secured against rotation on a shaft 384 journaled in a bracket 384' mounted on the workhead and said shaft has a horizontally extending arm 385 which engages the upper end of a vertical plunger 386 40 in a sleeve 387 provided by the bracket 384'. A cam 388 secured to the shaft 384 between the plate 345 and the roll 206 engages, during the rotation of the shaft 384, with the lower end of the plunger 386 urging the latter upwardly to 45 procure a clockwise turning movement of the arm 383, thereby releasing the rearmost workpiece in the groove 380. A depending arm 385' secured to the shaft 384 engages a spring 390 which is positioned between the sleeve 387 and 50 said arm and which retains the arm 383 in the normal position shown.

55 The ejector arm 346, as shown in Figs. 2 and 4, is of a sufficient width to prevent the rearmost workpiece *a* in the groove 380, when released by the arm 383, from dropping between the groove 382 and the roll 206 beneath said ejector arm. As the ejector arm returns counterclockwise to the position shown in full lines in Fig. 2, this movement occurring as the workhead moves into 60 operative position for a subsequent grinding operation, the workpiece *a* follows said arm downwardly, guided by the groove 382, so that said workpiece is properly positioned in the work-supporting member in readiness for a grinding operation. 65

65 As above stated, the finished workpiece is discharged when the ejector reaches the upper dot-dash line position of Fig. 2. From this position, the finished workpiece rolls by gravity toward the 70 rear of the machine over a guide 391 secured to the workhead and having a downwardly and rearwardly inclined surface 392 at its upper end. The forward edge of the surface 392 is positioned close to the periphery of the roll 206 so that the 75

finished workpiece passes over the surface 392 and onto a surface 393 provided by the end of an arm 394 journaled on a stud 395 positioned in a rearwardly extending portion 396 of the bracket 384. The portion 396 provides a rearwardly and downwardly inclined surface 397, the forward edge of which is normally positioned above the surface 393 a sufficient distance to stop the rearward movement of the discharged workpiece so that the rapid movement of the latter resulting from the action of the ejector arm 346 is checked and the workpiece is brought to rest in the dot-dash line position shown.

The arm 394 has a downwardly projecting arm 398 which has a roller 400 on the outer end thereof in alignment with a cam 401 on a guard 402 projecting upwardly from the base of the machine at the rear thereof. After the workpiece reaches the position shown in dotted lines above the surface 393, the arm 394 is rocked upwardly by the cam 401 during the movement of the table to rest position, thereby lifting the surface 393 into alignment with the surface 397 to allow the workpiece to roll slowly down the surface 397 and be discharged.

To make the grinding machine entirely automatic and to avoid the necessity for manual starting of the machine for each successive grinding operation, the table carries a block 403 which is provided with a cam member 404 in alignment with the upper end of the upwardly projecting arm 255. As the table moves to the left and just before the table reaches the rest position shown, the cam member 404 rocks the arm 255 downwardly a small amount to permit a depending dog 405 on the block 403 in back of the cam member 404 to engage with the upwardly extending portion 271 of the reversing lug 15, thereby reversing the table movement and procuring a return of the workhead to operative position. Since the portion 323' of the valve 122 is wider than the lower end of the arm 322 engaging therewith, the slight turning movement of said arm resulting from the downward movement of the arm 255 by the cam 404 does not change the position of said valve.

The lever 262 is returned to the original position of Fig. 1, with the horizontal arm 263 thereof out of alignment with the upwardly extending arms 257 and 316, by a bracket 406 secured to the control box 42 and having a flat upper surface 407 which engages with the arm 263 of said lever as the table reaches the end of its extended movement. The bracket 406 rocks the lever 262 counterclockwise for returning said lever to the original position shown, in readiness for a clockwise turning movement in response to entry of the gages within the bore of the workpiece during the subsequent grinding operation.

The operation of the machine which will doubtless be clear from the foregoing description will be briefly summarized. With the table at the end of its extended movement, as shown in Fig. 1, the ejector arm is in the dot-dash line position of Fig. 2 and the arm 383 is also in the dot-dash line position to permit the rearmost workpiece in the groove 380 to roll rearwardly onto the surface of the ejector arm 346. At this time, the finished workpiece has been discharged, by the upward movement of the ejector, to the dot-dash line position indicated, and the arm 214 carrying the pressure roll 213 has been rocked counterclockwise (Fig. 2) to permit the finished workpiece to be discharged from the work-sup-

porting structure and the unground workpiece to be properly positioned within said structure. The valve member 128 at this time is in the position of Fig. 11, into which position it was moved directly following the dressing operation during the preceding grinding operation, and the valve member 122 is in the extreme right hand position into which it was shifted at the end of the preceding grinding operation.

Assuming that the table has been brought to rest by turning of the throttle valve 191 to cut off the flow of fluid from the pipe 186 into the pipe 193 and also from the pipe 197 into the pipe 193, movement of the table to the right for positioning the workhead in operative relation to the grinding wheel is procured by turning said throttle valve 191 by means of the lever 204 on the front of the control box. Fluid under pressure is then directed from the pump through the pipes 117 and 186 and through the notch 194 of the throttle valve to the left hand end of the cylinder 25, the reversing valve 20 having previously been shifted, by the reversing dog 405, from the position shown into its opposite position in which fluid connection is provided between the ports 17 and 22 of the valve casing. The table then moves to the right into operative position at the maximum rate of speed.

During the movement of the workhead to operative position, the ejector arm 346 is swung counterclockwise and the workpiece 'a' follows said ejector arm downwardly in the groove 382 of the bracket 376 until it reaches the proper grinding position in engagement with the regulating wheel 206 and the supporting roll 207. The ejector arm continues downwardly into the full line position of Fig. 2 where it remains during the entire grinding operation. The turning movement of the ejector arm which is responsive to movement of the table also permits the pressure roller 213 to be returned to operative engagement with the workpiece by the spring 373 which resiliently retains said roller against the workpiece.

During the movement of the workhead into operative position, the depending dog 272 engages the upwardly extending arm 255 and rocks said arm downwardly, thereby returning the depending arms 246 and 322 to the original positions of Fig. 1. Since the gage members are still retained at their extreme left hand end of movement by fluid under pressure in the bore 334, the levers 241 and 317 are free to move so that the latches 243 and 318 of said levers engage the notches on the depending arms and retain them in their original position. During the return movement of the arm 246 to original position, the latch 275 is released to permit a subsequent movement of the arm 246 to the right, and the lever 292 returns to the position of Fig. 1 for limiting the left hand movement of the valve 122 during the subsequent grinding operation.

Return of the depending arm 322 to original position shifts the valve 122 to the mid-position of Fig. 11, thereby cutting off the flow of fluid through the pipe 186 and directing fluid under pressure through the pipes 124 and 197 to the throttling notch 200 of the reversing valve so that the movements of the table in operative position occur at a rate determined by the setting of the valve 191. Movement of the valve 122 to mid-position also permits fluid from the bore 334 to exhaust and also provides for exhaust of fluid from the upper end of the cylinder 116. When the pipe 145 communicating with the upper end

of the cylinder 116 is connected to the exhaust, the valve 328 returns to the position of Fig. 11, thereby directing fluid under pressure through the pipe 143 to the lower end of the cylinder 116 and the crossfeed movement is started, this crossfeed movement occurring at the rate determined by the setting of the valve 160.

The workpiece in the workhead having reached operative position, it is reciprocated axially over the surface of the grinding wheel under the control of the dogs 8 and 10 with the gage member 223 attempting on each reciprocation to enter the bore of the workpiece, said gage being urged to the right by the spring 235. Grinding continues with the workpiece reciprocating over the grinding wheel and with the crossfeed movement occurring at the rough grinding rate determined by the setting of the valve 160 until the roughing gage 223 enters the bore of the workpiece, thereby rocking the lever 241 to procure an upward movement of the arm 255 and a corresponding movement of the depending arm 246 to the right. Upward movement of the arm 255 renders inoperative the reversing dog 10 for an extended movement of the table to the left for a dressing operation on the grinding wheel. The movement of the arm 246 to the right shifts the valve 128 to the right, thereby reducing the rate of movement of the table by directing fluid under pressure past the auxiliary throttle valve 131. At the same time, the flow of fluid to the cylinder 116 is temporarily cut off by the valve 128 so that no crossfeed movement occurs during the dressing operation.

During the extended movement for dressing, the lever 292 is rocked to permit the valve 122 to move to its left hand position and at the same time to position said lever to engage with the latch 275. The movement of the valve 122 to the left limits the flow of fluid under pressure into the pipe 124 for reducing the rate of reciprocation of the table during the remainder of the grinding operation.

The extended movement of the table for dressing is reversed by the dog 267 and during the return movement, the depending dog 272 returns the arm 255 to original position, thereby preventing a repetition of the dressing operation, and also returns the depending arm 246 to original position where it is retained by the latch 275. Return of the arm 246 also returns the valve 128 to the position of Fig. 11 so that fluid under pressure again enters the cylinder 116 for continuing the crossfeed movement.

At a predetermined time during the grinding operation, the cam 108 urges the valve 163 downwardly to cut off the flow of fluid through the throttle valve 160 so that the remainder of the crossfeed movement occurs at a slower or finish grinding rate as determined by the setting of the throttle valve 172.

Following the dressing operation, the grinding operation continues until the finish gage 224 enters the bore of the workpiece, thereby rocking the lever 317 to permit the depending arm 322 to swing to the right, thus elevating the arm 255. Elevation of the arm 255 renders the dogs 10 and 267 both inoperative for an extended movement of the table to the left. Movement of the depending arm 322 to the right shifts the valve 122 to its extreme right hand position, thereby directing fluid under pressure to the upper end of the cylinder 16 for a retraction of the crossfeed movement during which movement the cam 108 is withdrawn from engagement with the valve

member 163 to permit the latter to return to original position. The valve 122 also directs fluid under pressure to the casing 327 for urging the valve 328 downwardly, thereby connecting the lower end of the cylinder 116 to the exhaust pipe 331, and also directs fluid under pressure to the bore 334 for retracting the gages 223 and 224 to the extreme left hand position of Fig. 3 out of the bore of the workpiece. Fluid under pressure is also directed by the valve 122 through the pipe 186 to the reversing valve so that the extended movement of the table to the left occurs at the maximum rate of speed.

During the extended movement of the table after the completion of the grinding operation, the ejector arm 346 is rocked clockwise (Fig. 2) for carrying the finished workpiece upwardly through the groove 382 and for discharging said workpiece toward the rear of the machine, the workpiece being brought to rest in the dot-dash line position indicated. A slight further movement of the table to the left, after the workpiece reaches the dot-dash line position, elevates the arm 394 to bring the surface 393 into alignment with the surface 391 so that the workpiece is discharged from the machine. Before the ejector arm 346 moves into engagement with the finished workpiece during its upward movement, the pressure roll 213 is rocked counterclockwise (Fig. 2) through the medium of the cam 358 on the ejector shaft. As the ejector reaches its upper or dot-dash line position, the arm 383 is raised to permit the rearmost workpiece in the groove 380 to roll onto the surface of said ejector as above stated.

As the table reaches the position of Fig. 1, the cam member 404 rocks the arm 255 downwardly to permit the depending dog to actuate the reversing member 18, thereby reversing the table movement and returning the workhead to operative position. The grinding operation is then repeated in the manner above outlined.

The ejector and the workloading structure is arranged for use with a plurality of similar workpieces which are to be ground simultaneously in the machine. It will be apparent from a consideration of Figs. 1 to 4 inclusive that the single workpiece shown might as easily consist of a plurality of workpieces of less length. In this case, the ejector arm 346 which, as shown in Fig. 4, extends across the entire outer surface of the regulating wheel 206 will engage beneath each of the workpieces for carrying all of them as a unit upwardly in the groove 382, said groove acting to retain said workpieces in position on the surface of the ejector arm 346 during their upward movement. As shown in Fig. 2, the lower end of the bracket 376 projects downwardly into radial alignment with a portion of the workpieces when the latter are in grinding position and aids in retaining said workpieces in proper alignment with each other during the grinding as well as during the loading of said workpieces and the ejection or discharge thereof. It will be noted that the gage members are retained to the left within the annular flange of the backing plate during the time that the ejector mechanism is discharging the finished workpiece and directing the unground workpiece into proper position within the supporting structure.

We claim,

1. In apparatus of the class described, a work-supporting structure comprising a rotating drive wheel engaging with the periphery of a workpiece, a supporting member engaging said work-

- piece, a pressure member resiliently engaging said workpiece for holding said workpiece in engagement with the drive wheel and the support, and a backing plate engaging the workpiece to prevent axial movement thereof in the work-supporting structure, and a plug gage member axially slidable within the backing plate for entry within the bore of the workpiece when the latter reaches a desired size.
10. 2. In a grinding machine, a grinding member and a work-supporting member, a table on which one of said members is mounted, means operable during the progress of the grinding operation for procuring a movement of the table for a dressing operation on the grinding member, hydraulically actuated means independent of the table moving means for procuring a crossfeed movement between said members, and means for discontinuing the crossfeed movement during the dressing operation.
15. 3. In a grinding machine, a grinding member and a work-supporting member, means, including a piston and cylinder, for procuring a crossfeed movement between said members, means operable during the grinding operation for procuring a dressing operation on the grinding member, and valve means actuated in response to said last means for discontinuing the flow of fluid under pressure to said crossfeed means during the dressing operation.
20. 4. In a grinding machine, a grinding member and a work-supporting member, hydraulically actuated means for procuring a crossfeed movement between said members, and means under the control of said crossfeed movement for reducing the flow of fluid to said hydraulically actuated means, thereby diminishing the rate of said crossfeed movement.
25. 5. In a grinding machine, a grinding member and a work-supporting member, hydraulically actuated means for procuring a crossfeed movement between said members, and valve means actuated in response to the cross-feed movement for reducing the flow of fluid to the hydraulically actuated means for diminishing the rate of said crossfeed movement.
30. 6. In a grinding machine, a grinding member and a work-supporting member, hydraulically actuated means for procuring a crossfeed movement between said members, said means including a piston and cylinder, means for directing fluid under pressure to one end of said cylinder at a predetermined rate, means operable during the grinding operation for procuring a dressing operation on the grinding member, and valve means for cutting off the flow of fluid to said cylinder during the dressing operation.
35. 7. In a grinding machine, a grinding member and a work-supporting member, hydraulically actuated means for procuring a cross-feed movement between said members, said means including a piston and cylinder, means for directing fluid under pressure to one end of said cylinder at a predetermined rate, means operable during the grinding operation for procuring a dressing operation on the grinding member, and valve means automatically operable for cutting off the flow of fluid to said cylinder during the dressing operation.
40. 8. In a grinding machine, a grinding member and a work-supporting member, hydraulically actuated means for procuring a crossfeed movement between said members, said means including piston and cylinder elements, one of said ele-

ment, means for procuring a retraction of the crossfeed movement at the completion of a grinding operation, and means automatically operable during the retractive movement for compensating for the wear on the grinding member.

9. In a grinding machine, a grinding member and a work-supporting member, hydraulically actuated means for procuring a crossfeed movement between said members, said means including piston and cylinder elements, one of said elements having a predetermined limited movement, means for procuring a dressing operation on the grinding member during the grinding operation, means for procuring a retraction of the crossfeed movement at the completion of a grinding operation, and means automatically operable during the retracting movement for compensating for the wear on the grinding member.

10. 10. In a grinding machine, a grinding member and a work-supporting member, means for procuring a crossfeed movement between said members, said means including a piston and cylinder, means for directing fluid under pressure to one end of said cylinder, manually adjusted throttle valves for controlling the amount of fluid under pressure entering said cylinder during the grinding operation, and means under the control of the crossfeed movement for rendering one of said throttle valves inoperative and for procuring a change in the rate of crossfeed movement.

11. 11. In a grinding machine, a grinding member and a work-supporting member, means for procuring a crossfeed movement between said members, said means comprising a cross-slide on which one of said members is mounted, a crossfeed screw for actuating said slide, a piston and cylinder, one of which is connected to the crossfeed screw for rotating said screw, means for directing fluid under pressure at a predetermined rate to one end of said cylinder for advancing said members relative to each other at a predetermined rate, and means for procuring a change in the rate of crossfeed movement in response to said movement.

12. 12. In a grinding machine, a grinding member and a work-supporting member, means for procuring a crossfeed movement between said members, said means comprising a cross-slide on which one of said members is mounted, a crossfeed screw for actuating said slide, a piston and cylinder, one of which is connected to the crossfeed screw for rotating said screw, means for directing fluid under pressure at a predetermined rate to one end of said cylinder for advancing said members relative to each other at a predetermined rate, means for procuring a change in the rate of crossfeed movement in response to said movement and means operable when a workpiece in the work-supporting member reaches the desired size for retracting the crossfeed movement.

13. 13. In a grinding machine, a grinding member and a centerless work-supporting member, means governed by the progress of the grinding operation for procuring an axial separation between said members when the workpiece in the work-supporting member reaches the desired size, an ejector, and means responsive to said axial separation for rocking said ejector upwardly to discharge the workpiece radially from the work-supporting member, said ejector, during its subsequent downward movement, directing an unground workpiece into the work-supporting member.

14. 14. In a grinding machine, a grinding member

- and a work-supporting member, the latter comprising a rotatable regulating wheel engageable with the workpiece in said member, a support, and a pressure member for resiliently holding the workpiece in engagement with said wheel and support, an ejector normally extending beneath the workpiece in the supporting member, and means operable upon the completion of the grinding operation for rocking said ejector arm upwardly to discharge the workpiece radially from the supporting member, said ejector arm, during its subsequent downward movement, directing an unground workpiece in the work-supporting member.
15. In a grinding machine, a grinding member and a work-supporting member, the latter comprising a rotatable regulating wheel engageable with the workpiece in said member, a support and a pressure member for resiliently holding the workpiece in engagement with said wheel and support, an ejector normally extending beneath the workpiece in the supporting member, means operable upon the completion of the grinding operation for rocking said ejector arm upwardly to discharge the workpiece radially from the supporting member, and other means operable at the completion of the grinding operation for spacing the pressure member from the workpiece to permit discharge of the workpiece from the work-supporting member.
20. In a grinding machine, a grinding member and a work-supporting member, the latter comprising a rotatable regulating wheel engaging the periphery of a workpiece in said member, a support engaging the periphery of said workpiece beneath the axis thereof, a pressure wheel for resiliently urging said workpiece into engagement with the regulating wheel and support, a table on which one of said members is mounted, means for procuring an extended movement of said table for an axial separation between said members when the workpiece in the work-supporting member reaches the desired size, and an ejector normally positioned below said workpiece and actuated directly in response to movement of the table for removing the finished workpiece from the work-supporting member and for directing an unground workpiece into said work-supporting member.
25. In a grinding machine, a grinding member and a work-supporting member, the latter comprising a rotatable regulating wheel engageable with the periphery of a workpiece, a work-support beneath said workpiece, and a pressure member engaging the periphery of said workpiece and resiliently retaining the latter in engagement with said wheel and support, an ejector for discharging the finished workpiece radially from the work-supporting member, a gage adapted to enter the bore of the workpiece when the latter is ground to the proper size, and means responsive to the entry of said gage and independently of the operation of said ejector for retracting said gage from the bore of the workpiece prior to the discharge of the finished workpiece and the positioning of an unground workpiece in the work-supporting member.
30. In a grinding machine, a grinding member and a work-supporting member, the latter comprising a rotatable regulating wheel engageable with the periphery of a workpiece, a work-support beneath said workpiece and a pressure member engaging the periphery of said workpiece and resiliently retaining the latter in engagement with said wheel and support, a table on which one of said members is mounted, means operable at the completion of a grinding operation for procuring an extended movement of the table for an axial separation between said member, and an ejector having an arm thereof extending beneath the workpiece and parallel to the periphery of the regulating wheel, said ejector being rocked upwardly in response to the extended movement for radial discharge of the finished workpiece.
35. In a machine for the successive reduction of workpieces to a predetermined size, a grinding member and a work-supporting member, hydraulically actuated means for procuring a cross-feed movement between said members, an ejector normally positioned beneath the workpiece in the work-supporting member, automatically operable means for rocking said ejector upwardly for discharging the finished workpiece radially from the work-supporting member, said ejector, during its subsequent downward movement, directing an unground workpiece into the work-supporting member, and valve means operable upon the workpiece reaching the desired size for procuring retraction of the crossfeed movement.
40. In a machine for successive reduction of a plurality of workpieces all to the same predetermined size, a grinding member and a work-supporting member, a table on which one of said members is mounted, hydraulically actuated means for procuring a crossfeed movement between said members, means operable when the work-piece in the work-supporting member
45. In a grinding machine, a grinding member and a work-supporting member, the latter comprising a rotatable regulating wheel engageable with the periphery of a workpiece, a work-support beneath said workpiece and a pressure member engaging the periphery of said workpiece and resiliently retaining the latter in engagement with said wheel and support, a table on which one of said members is mounted, means operable at the completion of a grinding operation for procuring an extended movement of the table for an axial separation between said member, and an ejector having an arm thereof extending beneath the workpiece and parallel to the periphery of the regulating wheel, said ejector being rocked upwardly in response to the extended movement for radial discharge of the finished workpiece.
50. In a grinding machine, a grinding member and a work-supporting member, the latter comprising a rotatable regulating wheel engageable with the periphery of a workpiece, a work-support beneath said workpiece and a pressure member engaging the periphery of said workpiece and resiliently retaining the latter in engagement with said wheel and support, a table on which one of said members is mounted, means operable at the completion of a grinding operation for procuring an extended movement of the table for an axial separation between said member, and an ejector having an arm thereof extending beneath the workpiece and parallel to the periphery of the regulating wheel, said ejector being rocked upwardly in response to the extended movement for radial discharge of the finished workpiece.
55. In a machine for the successive reduction of workpieces to a predetermined size, a grinding member and a work-supporting member, hydraulically actuated means for procuring a cross-feed movement between said members, an ejector normally positioned beneath the workpiece in the work-supporting member, automatically operable means for rocking said ejector upwardly for discharging the finished workpiece radially from the work-supporting member, said ejector, during its subsequent downward movement, directing an unground workpiece into the work-supporting member, and valve means operable upon the workpiece reaching the desired size for procuring retraction of the crossfeed movement.
60. In a machine for successive reduction of a plurality of workpieces all to the same predetermined size, a grinding member and a work-supporting member, a table on which one of said members is mounted, hydraulically actuated means for procuring a crossfeed movement between said members, means operable when the work-piece in the work-supporting member
65. In a grinding machine, a grinding member and a work-supporting member, the latter comprising a rotatable regulating wheel engageable with the periphery of a workpiece, a work-support beneath said workpiece and a pressure member engaging the periphery of said workpiece and resiliently retaining the latter in engagement with said wheel and support, a table on which one of said members is mounted, means operable at the completion of a grinding operation for procuring an extended movement of the table for an axial separation between said member, and an ejector having an arm thereof extending beneath the workpiece and parallel to the periphery of the regulating wheel, said ejector being rocked upwardly in response to the extended movement for radial discharge of the finished workpiece.
70. In a machine for successive reduction of a plurality of workpieces all to the same predetermined size, a grinding member and a work-supporting member, a table on which one of said members is mounted, hydraulically actuated means for procuring a crossfeed movement between said members, means operable when the work-piece in the work-supporting member
75. In a grinding machine, a grinding member and a work-supporting member, the latter comprising a rotatable regulating wheel engageable with the periphery of a workpiece, a work-support beneath said workpiece and a pressure member engaging the periphery of said workpiece and resiliently retaining the latter in engagement with said wheel and support, a table on which one of said members is mounted, means operable at the completion of a grinding operation for procuring an extended movement of the table for an axial separation between said member, and an ejector having an arm thereof extending beneath the workpiece and parallel to the periphery of the regulating wheel, said ejector being rocked upwardly in response to the extended movement for radial discharge of the finished workpiece.

reaches the desired size for procuring an extended movement of the table for an axial separation between said members, an ejector normally positioned beneath the workpiece in the work-supporting member and actuated in response to said extended movement for discharging the finished workpiece and positioning an unground workpiece in the work-supporting member, and means responsive to the table movement for reversing the table at the end of the extended movement.

23. In a machine for successive reduction of a plurality of workpieces all to the same predetermined size, a grinding member and a work-supporting member, a table on which one of said members is mounted, hydraulically actuated means for procuring a crossfeed movement between said members, size-determining means, means responsive to said size-determining means for procuring an extended movement of the table, a valve member actuated by said size-determining means for procuring reversal of the crossfeed movement and retraction of the size-determining means from the bore of the workpiece, an ejector for discharging the finished workpiece from the work-supporting member and for positioning an unground workpiece therein, means for reversing the table at the end of the extended movement, and means operable during the return of said table to operative position for resetting said valve member to permit the size-determining means to engage the workpiece in the work-supporting member and to procure the crossfeed movement.

24. In a grinding machine, a grinding member and a work-supporting member, the latter comprising a rotatable regulating wheel engageable with the workpiece in said member, a work sup-

port, and a pressure member for resiliently holding the workpiece in engagement with said wheel and support, an ejector normally extending beneath the workpiece in the supporting member, means operable upon the completion of the grinding operation for rocking said ejector arm upwardly to discharge the workpiece radially from the supporting member and for spacing the pressure member from the workpiece to permit discharge of said workpiece; a gage member whose entry within the bore of the workpiece indicates the completion of the grinding operation, and means automatically operable prior to operation of the ejector actuating means for retracting said gage from within the bore of the workpiece.

25. In a grinding machine, a grinding member and a work-supporting member, the latter comprising a rotatable regulating wheel engageable with the workpiece in said member, a work support, and a pressure member for resiliently holding the workpiece in engagement with said wheel and support, a gage member whose entry within the bore of the workpiece procures an axial separation of the grinding member from the workpiece, an ejector normally extending beneath the workpiece in the supporting member, means operable upon the completion of the grinding operation and in response to said axial separation for actuating said ejector arm to discharge the workpiece radially from the supporting member and for spacing the pressure member from the workpiece, and means responsive to entry of the gage within the workpiece for retracting said gage from the bore thereof prior to the discharge of the finished workpiece.

HAROLD L. BLOOD.
ALFRED P. BURNS.
